UNITED STATES PATENT OFFICE

109,977

DESIGN FOR A CASKET

Joseph A. Christian, Chicago, Ill.

Application April 11, 1938, Serial No. 76,430

Term of patent 3½ years

To all whom it may concern:

Be it known that I, Joseph A. Christian, a citizen of the United States, residing at Chicago, in the county of Cook and State of Illinois, have invented a new, original, and ornamental Design for a Casket, of which the following is a specification, reference being had to the accompanying drawing, forming part thereof.

In the drawing,

Fig. 1 is a side elevation of a casket showing my new design; and

Fig. 2 is an end elevation thereof.

I claim:

The ornamental design for a casket, as shown.

JOSEPH A. CHRISTIAN.
